(57) **CLAIM**

The ornamental design for an adjustable end cap beam for a pallet rack, as shown and described.

DESCRIPTION

FIG. 1 is a rear perspective view of the new design for an adjustable end cap beam for a pallet rack.

FIG. 2 is a front perspective view thereof;

FIG. 3 is a rear elevational view of the new design of FIG. 1.

FIG. 4 is a front elevational view of the new design of FIG. 1.

FIG. 5 is a bottom view of the new design of FIG. 1. The top view is a mirror image of the bottom view.

FIG. 6 is a left-side elevational view of the new design of FIG. 1; and,

FIG. 7 is a right-side elevational view of the new design of FIG. 1.

The broken lines in FIGS. 1-7 are for illustrating the environment of the design only and form no part of the claimed design.

The dash-dot-dash broken lines adjacent to the shaded areas represent the bounds of the claimed design and form no part thereof.
